BUTTONING POST

David A. Freeman, Drake Hotel, 140 E. Walton St.,
Chicago, Ill.

Filed Aug. 14, 1958, Ser. No. 52,200

Term of patent 14 years

(Cl. D49—1)

The dominant features of my new design reside in those portions shown in full lines.

I claim:

The ornamental design for a buttoning post, substantially as shown and described.
